TYPEWRITER CARRYING CASE

Alejandro De Tomaso, % Ghia S.p.A., Via A. Da Monte-feltro 5, and Thom Tjaarda, Str. Ponteverde 12, both of Turin, Italy

Filed Oct. 25, 1972, Ser. No. 300,549
(Filed under Rule 47(b) and 35 U.S.C. 118)

Term of patent 14 years

Int. Cl. D3—02

U.S. Cl. D87—1 R

FIG 1

FIG. 1 is a front perspective view of a typewriter carrying case showing our new design;

FIG. 2 is a top plan view with the handle in extended position;

FIG. 3 is a front elevational view thereof;

FIG. 4 is a bottom plan view thereof;

FIG. 5 is a right side elevational view thereof; and

FIG. 6 is a rear elevational view

We claim:

The ornamental design for a typewriter carrying case, substantially as shown and described.
